UNITED STATES PATENT OFFICE

120,175

DESIGN FOR AN ORGAN CONSOLE

George H. Stephens, Glencoe, Ill., assignor to Hammond Instrument Company, Chicago, Ill.,
a corporation of Delaware

Application September 8, 1939, Serial No. 87,093

Term of patent 14 years

To all whom it may concern:

Be it known that I, George H. Stephens, a citizen of the United States, residing at Glencoe, in the county of Cook and State of Illinois, have invented a new, original, and ornamental Design for an Organ Console, of which the following is a specification, reference being had to the accompanying drawing, forming part thereof.

The drawing is a perspective view of an organ console, showing my design.

I claim:

The ornamental design for an organ console, as shown.

GEORGE H. STEPHENS.
